UNITED STATES PATENT OFFICE.

LEONARD E. CLAWSON, OF SAN FRANCISCO, CALIFORNIA.

CYLINDER-GRINDER.

1,154,378.

Specification of Letters Patent. Patented Sept. 21, 1915.

Application filed March 30, 1915. Serial No. 18,070.

To all whom it may concern:

Be it known that I, LEONARD E. CLAWSON, a citizen of the United States, residing in the city and county of San Francisco and 5 State of California, have invented new and useful Improvements in Cylinder-Grinders, of which the following is a specification.

My invention relates to a device for grinding and finishing the interior of cylinders 10 and like surfaces to any desired degree of accuracy and smoothness.

It consists of a longitudinally grooved head centered and adapted to move within the cylinder or surface to be ground, and 15 having a means for supplying a multitude of small balls together with a suitable grinding or abrasive substance and feeding them down through the longitudinal channels of the grinding head so that they contact with 20 and grind the interior of the cylinder as the head is moved downwardly, and by an inclination of the grooves or channels the balls are constantly fed downward and held to their work.

25 It also comprises details of construction which will be more fully explained by reference to the accompanying drawings, in which—

Figure 1 is a longitudinal section of 30 a cylinder and partially of the grinding head, showing also the channels and balls within. Fig. 2 is a horizontal section through the same. Figs. 3 and 5 are sectional views showing channeled ball carriers varied to 35 suit different sizes of cylinders. Fig. 4 is a sectional view of a cylinder, showing the grinding head guided to move centrally through the cylinder.

The object of this invention is to provide 40 a means for grinding and finishing the interior of cylindrical surfaces.

As shown in the drawings, A represents 45 a cylinder of any suitable construction, the interior of which it is desired to finish.

2 is a head mounted upon a shaft 3 which is guided in bearings, at top and bottom, as shown at 4, so that the head will be maintained in proper central position with relation to the cylinder. This head has 50 grooves or channels made in it, as shown at 5. These grooves are preferably inclined from the top toward the bottom and are adapted to receive a large number of small balls having a quality of wearing or grinding 55 away any surface with which they are brought into forcible contact. These balls

passing down the channels project slightly therefrom against the interior of the cylinder, and upon the head being turned around within the cylinder the balls will be carried 60 around so as to grind the interior surface and gradually reduce it to a perfectly even polished condition. The balls will move down the inclined grooves gradually as the wear proceeds and will eventually be discharged at the lower end.

The movement of the balls through the cylinder may be effected by gradually feeding the grinding head down through the cylinder either by gravitation or by direct 70 force. The upper end of the grinding head is formed with a hollow receiving section, as at 6, into which the balls 7 are discharged in quantities, and the top of the head has an outwardly curved, chambered portion, as 75 at 8, which directs the balls downwardly and into the channels or grooves 5. Any suitable number of the grooves or channels may be employed, as shown in Fig. 2.

In Figs. 3 and 5 I have shown guides 9 80 fitted to the channels by dovetailing, or other equivalent means, so that they can be slipped into position and retained there. These guides are grooved or channeled on the outer face so as to receive the balls and retain them 85 in position to be carried around inside of the cylinder, as before described. The guides are made of different depths radially so that different sets of guides may be used according to the size of the cylinder. Thus 90 a set of the guides may be employed which project very slightly from the face of the head and will serve for a certain size of cylinder, while if a larger sized cylinder is to be used a set of guides projecting far- 95 ther, as shown in Fig. 5, will carry the balls out to grind the interior of the larger cylinder. Work may thus be performed very accurately and rapidly.

It will be obvious that by the inclination 100 of the ball channels and the revolution of the head, as shown by the arrow a, the balls will be fed downwardly automatically as the head rotates.

Having thus described my invention, what 105 I claim and desire to secure by Letters Patent is—

1. A grinding tool for the interior of cylinders comprising a revoluble head with a vertical axis coincident with that of the cylinder to be ground, said head having diagonally disposed open ended channels from end

to end, grinding balls movable through the channels of the head, with their surfaces contacting with the interior of the cylinder, and means to constantly advance the balls between the head and cylinder.

2. A cylinder grinding tool comprising a vertically journaled head axially coincident with the cylinder to be ground, open ended channels extending diagonally from end to 10 end of the head, grinding balls movable by gravitation through the said channels, and peripherally contacting with the cylinder and means to deliver balls continuously to the channels.
- 15 3. In a cylinder grinding tool, a vertically journaled head axially revoluble within the cylinder, open ended guide channels extending diagonally from end to end of the head, balls movable by gravitation through the 20 channels with their surfaces in contact with the cylinder interior, a source of supply

above the head with inclined passages through which the balls are continuously delivered to the channels.

4. In a cylinder grinding tool, a vertically 25 journaled head axially revoluble within the cylinder to be ground, dovetailed open ended channels extending diagonally from end to end of the head, guides fitting said channels and having grooves in the surfaces, 30 balls movable by gravitation through the grooves with their surfaces in contact with the cylinder interior, said guides being interchangeable to fit the channels to cylinders of different sizes.

35 In testimony whereof I have hereunto set my hand in the presence of two subscribing witnesses.

LEONARD E. CLAWSON
